OTHER PUBLICATIONS

Advertisement by Land O' Lakes showing a personal size container for beverages, trademarked as the "Grip." It also has a resealable top.

U.S. patent application Ser. No. 29/155,324 filed on Mar. 11, 2003, "Snack Food Container".

Primary Examiner—Carol Rademaker

(74) Attorney, Agent, or Firm—Colin P. Cahoon; Carstens, Yee & Cahoon, LLP

(57) **CLAIM**

The ornamental design for a snack food container, as shown and described.

DESCRIPTION

FIG. 1 is a front, top perspective view of the snack food container of the present invention;

FIG. 2 is a front elevation view of the snack food container of the present invention;

FIG. 3 is a left elevation view of the snack food container of the present invention, the right elevation view being a mirror image of the left elevation view;

FIG. 4 is a rear elevation view of the snack food container of the present invention;

FIG. 5 is a top plan view of the snack food container of the present invention; and,

FIG. 6 is a bottom plan view of the snack food container of the present invention.

1 Claim, 3 Drawing Sheets
